UNITED STATES PATENT OFFICE.

WILLIAM U. GRIFFITHS, OF PHILADELPHIA, PENNSYLVANIA.

VALVE-OPERATING MECHANISM FOR WATER-CLOSETS.

1,104,887.

Specification of Letters Patent. Patented July 28, 1914.

Application filed July 18, 1913. Serial No. 779,690.

To all whom it may concern:

Be it known that I, WILLIAM U. GRIFFITHS, a citizen of the United States, and a resident of Philadelphia, in the county of 5 Philadelphia and State of Pennsylvania, have invented certain new and useful Improvements in Valve-Operating Mechanism for Water-Closets, of which the following is a specification.

10 My invention relates to improvements in valve operating mechanism for water closets, and it has for its object to provide an improved mechanism whereby a water closet hopper may be automatically flushed.

15 My invention comprehends the construction and arrangement of parts as illustrated in the accompanying drawing and as is particularly described and pointed out in the claims. It will be understood, however, 20 that changes in the details of construction within the scope of the claims may be made without departing from my invention.

In the drawings:—Figure 1 is a view showing partly in side elevation and partly 25 in vertical longitudinal section, a construction of apparatus embodying my invention; Fig. 2 is a view showing the flush tank in cross section with the valve and valve operating parts therein in front elevation; and 30 Fig. 3 is a view showing a detail of construction.

In the drawings, 1 designates a water closet hopper (the top portion only of which is shown), and 2 designates the seat therefor 35 pivoted at 3. The seat is provided with arms 4 extending rearwardly therefrom and having their rear ends connected by a cross-piece 5 which acts as a weight to tilt the seat 2 as shown in Fig. 1. The cross-piece 5 40 is provided with an undercut slot 6 for a purpose to be hereinafter described.

10 designates a flush tank which is substantially rectangular in cross section, as is indicated, the width of the same being considerably greater than its thickness from front to rear. My invention, however, is not dependent upon the shape of the tank, although it is well adapted for use in a tank of the character shown. Water enters the 50 flush tank through pipe 10^a. The said tank is provided with a port or opening 11 in its bottom through which a flush pipe 12, having connection at its lower end with the hopper 1, communicates with a siphon 13. 55 The flush pipe 12 constitutes, in fact, a con-

tinuation of one leg of the siphon 13. The opposite end of the siphon is open at all times as indicated at 14.

15 designates an opening into the longer leg of the siphon (regarding the flush pipe 60 12 as a part of such leg) which opening is closed by means of a valve 16 supported upon a lever 17 pivoted at 18. The said lever is provided with a slotted projection 20 in the slot of which an elbow lever 21 is 65 pivoted. One arm 22 of the lever 21 extends horizontally and is provided with a weight 23. Movement of the lever 21 to the right, having reference to Fig. 1 of the drawings, is limited by contact of the lower 70 edge of the arm 22 with the shoulder 24 upon the projection 20 between the ears formed by the slot therein. The upper end portion of the lever 21 is curved, as indicated at 25, to form a cam surface by means 75 of which the lever 21 and the arm 22 and weight 23 carried thereby are operated. Said lever 21 is also provided with an arm 26 extending from one end thereof which arm is curved downwardly as shown in 80 Fig. 2.

27 designates a lever pivoted intermediate its ends at 28 upon a lug preferably formed upon the siphon 13. One end of the said lever 27 is provided with a lateral projection 85 29 the end of which is adapted to engage the curved cam surface of the lever 21 when the said lever 27 is moved about its pivot so as to lower the said projection 29. When the said lever is moved about its pivot so as to 90 lower the end carrying the projection 29 the said projection first contacts with the curved side of the lever 21 to cause movement of the same about its pivot at 30. When the projection 29 reaches the position indicated by 95 dotted lines at 31 in Fig. 2 of the drawings, the weight 23 causes the lever 21 to turn about its pivot at 30 to return to normal upright position. Pivotal movement of the lever 21 thus effected does not affect the 100 valve 16 upon the lever 17. In returning the lever 27 to its normal position which it occupies in Fig. 2 of the drawings, the projection 29 catches underneath the arm 26 and lifts the lever 21 together with the lever 17, causing the latter to turn about its pivot 18 and thus open the valve 16. In returning from the dotted line position indicated at 31 to 105 normal position, the projection 29 and the arm 26 have sliding movement with respect 110

to each other, the projection 29 finally passing around the end of the said arm 26. The levers 21 and 17 then return to their normal position indicated in Fig. 1 of the drawings 5 to close the valve 16. In the meantime, however, sufficient water has passed through the valve opening 15 to start siphonic action.

For the purpose of effecting pivotal movement of the lever 27 so as to depress the projection 29, I have provided the rod 35, the 10 upper end portion of which is bent in two places, substantially at right angles to each other, so that its extreme end portion extends downwardly into the tank and is connected with the lever 27 at a point upon the 15 opposite side of its pivot 28 from the projection 29. The greater portion of the rod 35 is located outside of the flush tank 10 and its lower end is provided with an enlargement 20 or ball which is positioned within the undercut slot 6 as is illustrated in Fig. 1 of the drawing.

It will be seen that when the seat 2 is moved from the full line to the dotted line 25 position shown in Fig. 1 of the drawing, the arms 4 and connection 5 are moved upwardly causing an upward movement of the rod 35 and by reason of the connection of the upper end thereof to the end of the lever 27 as 30 indicated at 36 the said lever 27 is caused to move about its pivot 28 so as to carry the projection 29 downwardly underneath the arm 26. In moving to this position it causes 35 pivotal movement of the lever 21 as hereinbefore described. When the seat 2 returns from the dotted line position to the full line position shown in Fig. 2, the rod 35 is moved downwardly by its own weight and also by reason of the connection of its lower end 40 with the weight 5 so that the lever 27 is caused to move in a direction to carry the projection 21 upwardly from the dotted line position shown at 31 to the full line position 45 shown in Fig. 1 of the drawings. In doing so, it lifts the levers 17 and 21 as described.

I claim:

1. The combination of a valve adapted to be moved to open and close the same, a pivotal support for said valve, means having connection with said valve whereby the latter may be moved to open and close the same which means is movable independently of said valve, the said means having a part adapted to be engaged to effect movement of 50 the said valve and a movable member acting automatically to engage said part to effect movement thereof for the purpose stated.

2. The combination of a pivotal support having a valve carried thereby, a member 55 pivotally connected to said support and having a part adapted to be engaged for the purpose of effecting movement of said valve support to open said valve, and oscillatable means which when moving in one direction 60 engages the said member and causes pivotal

movement thereof and when moving in the opposite direction engages the said member and causes bodily movement thereof to lift said support and open said valve.

3. Mechanism of the character described, 70 comprising, in combination, a valve, a pivoted member having connection therewith, the said member having a weighted arm and also having a cam surface and a part adapted to be engaged to effect opening 75 of the said valve, an oscillatable member adapted when moved in one direction to engage the said cam surface and cause pivotal movement of the said pivoted member to permit passage of the said oscillatable member to a point underneath the said part and when moved in the opposite direction to engage said part and cause movement of said member to open said valve, and means for effecting oscillation of the said oscillatable member whereby the same is caused to engage the said part and open the said valve. 80

4. Mechanism of the character described, 90 comprising, in combination, a pivoted support having a valve connected thereto, a member pivotally connected with the said support and adapted to cause movement of the latter, the said member having a laterally extending arm and also a weighted arm whereby it is held in normal position, 95 a pivoted lever having a part which is adapted to engage the said pivoted member when moved in one direction to cause pivotal movement independently of the pivoted support, whereby the said pivoted lever may be 100 moved into position with a part thereof underneath the said arm, whereby when the said lever is moved in the opposite direction it will engage the said arm to lift the said pivoted member and the said support 105 to open the said valve, and means acting automatically to cause movement of the said pivoted lever.

5. In a valve mechanism adapted for use 110 in connection with water closet apparatus, the combination of a valve for closing a valve opening, a pivoted actuating member having connection with the said valve, the said actuating member being provided with an upwardly extending curved arm and also 115 with a downwardly and laterally extending arm, and also having a weight connected thereto to hold the same in normal position, a movable member adapted when moved in one direction to engage the said upwardly 120 extending curved arm to effect pivotal movement of the said actuating member whereby the said movable member may be passed into position with a part thereof underneath the downwardly extending arm and without 125 affecting said valve and whereby when the said movable member is moved in the opposite direction the said actuating member will be moved in a direction to open the said valve, and means for effecting movement of 130

the said movable member to actuate the said actuating member to cause opening and closing of the said valve.

6. In a valve mechanism adapted for use in connection with water closet apparatus, the combination of a valve for closing a port, an actuator having pivotal connection with the said valve, a pivot for said actuator, a pivoted member for actuating the said actuator, a pivot for said pivoted member, said last named pivot being arranged at right angles to the first named pivot, and the said actuator and pivoted member occupying parallel planes, the said actuator having an upwardly extending arm provided with a cam surface adapted to be engaged by a part of said pivoted member to cause

pivotal movement of the said actuator upon the downward movement of said part and the said actuator having a downwardly and laterally extending arm, the underneath edge of which is adapted to be engaged by a part of the said pivoted member as the same is moved upwardly to lift the said valve to open the same and means for effecting pivotal movement of the said pivotal member.

In testimony that I claim the foregoing as my invention, I have hereunto signed my name this 16th day of July, A. D. 1913.

WILLIAM U. GRIFFITHS.
